[57] CLAIM

The ornamental design for a razor holder, as shown.

DESCRIPTION

FIG. 1 is a front perspective view of a razor holder showing my new design;

FIG. 2 is a left side elevational view thereof;

FIG. 3 is a right side elevational view thereof;

FIG. 4 is a plan view of the top of the razor holder of FIG. 1;

FIG. 5 is a plan view of the bottom thereof;

FIG. 6 is an elevational view of the front thereof;

FIG. 7 is an elevational view of the rear thereof;

FIG. 8 is a bottom plan view of the holder in open position.
